UNITED STATES PATENT OFFICE.

JAMES L. POALK, OF MERCHANTVILLE, NEW JERSEY, ASSIGNOR OF ONE-HALF TO MORRIS LISSNER, OF PHILADELPHIA, PENNSYLVANIA.

DESIGN FOR A BUCKLE.

SPECIFICATION forming part of Design No. 38,577, dated November 20, 1900.

Application filed October 24, 1900. Serial No. 34,217. Term of patent 7 years.

To all whom it may concern:

Be it known that I, JAMES L. POALK, a citizen of the United States, residing at Merchantville, in the county of Camden and State of New Jersey, have invented and produced a new and original Design for a Buckle, of which the following is a specification, reference being had to the accompanying drawings, forming part hereof, in which—

Figure 1 is a top or plan view of a buckle of the design of my invention, and Fig. 2 is an end elevational view of the same.

As illustrated in the drawings, the leading or material feature of the buckle of my design consists of the shape or configuration of the same, having an oblong open body portion with side bars a and a' and ends b and b' , humped or projected at b^2 and b^3 to support a bar c , located with respect to the side bars a and a' beyond a median line drawn

transversely through the respective ends of the buckle. The buckle when viewed in plan and in end elevation shows the bar c elevated above the body portion of the buckle with the ends of the buckle carrying the bar c humped or projected and with the bar c positioned beyond a plane central to that of the buckle. 25

Having thus described my invention, what I claim as new, and desire to secure by Letters Patent, is—

The design for a buckle, substantially as shown and described.

In testimony whereof I have hereunto set my signature in the presence of two subscribing witnesses.

JAMES L. POALK.

Witnesses:

J. WALTER DOUGLASS,
THOMAS M. SMITH.
